UNITED STATES PATENT OFFICE.

WILLIAM E. SPARKS, OF NEW HAVEN, CONNECTICUT, ASSIGNOR TO SARGENT & CO., OF SAME PLACE.

IMPROVEMENT IN DRAWER-PULLS.

Specification forming part of Letters Patent No. 123,301, dated January 30, 1872.

To all whom it may concern:

Be it known that I, WILLIAM E. SPARKS, of New Haven, in the county of New Haven and State of Connecticut, have invented a new Improvement in Drawer-Pulls; and I do hereby declare the following, when taken in connection with the accompanying drawing and the letters of reference marked thereon, to be a full, clear, and exact description of the same, and which said drawing constitutes part of this specification, and represents, in—

Figure 1, a front view; Fig. 2, a vertical central section; and in Fig. 3, a longitudinal central section.

This invention relates to an improvement in the article of manufacture known to the trade as drawer-pulls. These have usually been constructed in a single piece, of shell form, secured directly to the drawer-front, so that the front of the drawer was exposed to contact with the fingers, which quickly defaces the front. The object of this invention is to overcome this difficulty, as well as to produce a more elaborate drawer-front; and it consists in combining with such a pull a plate, which forms a base on the drawer-front to avoid the aforesaid difficulty.

A is a drawer-pull proper, of style in accord-

ance with the taste of the manufacturer and requirements of the trade. B is a plate or base, of like desirable form, onto which the pull A is set, by preference a recess being formed in the plate at *a*, into which a corresponding projection on the pull will sit, for the purpose of accurately determining the relative position of the two parts. Screws *d*, inserted through the pull in the usual manner, secure both to the drawer-front.

Covering the drawer, as this plate does, beneath the drawer-pull and for some distance around it, the drawer-front is protected from contact with the fingers, and the pull may thereby be made highly ornamental; as, for instance, the plate may be of one kind or color of material and the pull of another.

Claim.

As an article of manufacture, the herein-described draw-pull, consisting of the pull A and the separate base or plate B, constructed to be set the one upon the other, and both secured to the drawer, substantially as set forth.
